**COMBINED LOUVER BLADE AND
BRACE THEREFOR**

**Joshua R. Dowell, Jr., Dallas, and Paul H. Sanderson,
Jr., Lake Dallas, Tex., assignors to Dowco Corporation,
Dallas, Tex.**

Filed June 17, 1970, Ser. No. 23,542

Term of patent 14 years

Int. Cl. D23—03

U.S. Cl. D23—112

FIG. 1

FIG. 3

FIG. 2

FIG. 4

FIG. 1 is a perspective view of a combined louver blade and brace therefor embodying our new design,

FIG. 2 is a bottom plan view thereof,

FIG. 3 is a front elevational view thereof, and

FIG. 4 is an end elevational view thereof on an enlarged scale.

We claim:

The ornamental design for a combined louver blade and brace therefor, as shown.
